BOWABLE ICE TRAY GRID WITH
PREFLEXED CROSS WALLS

Robert Lay Hallock, Larchmont, N. Y.

Application April 28, 1950, Serial No. 158,773

15 Claims. (Cl. 62—108.5)

1

My invention relates to improvements in ice tray grids that are distortable to release ice pieces, and more particularly grids that have resilient walls and which are bowable. A grid of this type is illustrated and described in my Patent No. 2,378,845 granted June 19, 1945.

The objects of the invention are to provide a grid of this type that is simpler and easier to construct and simpler and easier to operate.

This application replaces and relates back for common subject matter to my application S. N. 78,580 filed February 26, 1949, which is now abandoned.

Novel features that characterize this invention are resilient walls held in flexure while ice is being formed, and then unflexed to loosen ice attached thereto; a backbone, otherwise known as a center or longitudinal wall, fashioned from a single sheet of material in such a manner that it is bowable in its own plane; and members for bowing the grid, at least one of which is bowable with the grid.

These and other features of the invention, together with the advantages which they afford, appear in the following description and accompanying drawings in which:

Fig. 1 is a plan of an ice freezing tray and grid embodying the invention;

Fig. 2 is a section on line 2—2 in Fig. 1;

Fig. 3 is a detail section of a portion of Fig. 9; 30

Fig. 4 is a similar detail section of Fig. 10;

Fig. 5 is a detail partly in section showing a part of the grid referred to as a stop strap;

Fig. 6 is a detail section of another portion of Fig. 10;

Fig. 7 is a detail section of another portion of Fig. 8;

Fig. 8 is an exploded plan of two pieces in Fig. 7;

Fig. 9 is an elevation of the grid as illustrated in Fig. 1 with the ice tray in section;

Fig. 10 is a view like Fig. 9 showing the grid operated and removed from the tray; and

Fig. 11 is an elevation of the center wall or longitudinal partition only.

As seen in Figs. 1, 9 and 10, the ice tray grid is composed essentially of a center or longitudinal wall member or partition and a number of cross walls or partitions which intersect the center wall and form therewith a plurality of cells arranged in two rows. Operating members are provided to bow the grid, as shown in Fig. 10, to effect release of ice pieces formed in the cells.

The center or longitudinal wall is fashioned from a single sheet of material to the configura-

tion illustrated in Fig. 11. The material may be sheet metal or plastic sheet. 61ST8 aluminum sheet .051" in thickness, or 52SH aluminum sheet .060" in thickness has been found satisfactory. The wall strip 10 has a row of slits or slots near the bottom edge comprising a series of slots 11 and an alternate series of longer slots 12. Each of the shorter slots 11 has a curved slot 13 connecting it to the top edge of the strip 10. Each of the longer slots 12 is connected by a cut 14 to a respective upright slot 13. This leaves as the only section running the full length of the strip 10 a ribbon 15 at the bottom of the wall.

At the top end of each of the upright slots 13 there are lugs or ears or tabs, one on each side of the slot. These are numbered 16 to 27 inclusive and are of several shapes and sizes for purposes that appear below. The left end of the strip 10, as seen in Fig. 11, projects upward to form a section 28 provided with a hole 29 and a lug 30 which projects toward the lug 16. On the right hand end of the strip 10 there are two small upward projecting lugs 31 and 32. The wall strip 10 as just described and as illustrated in Fig. 11 is formed by one press operation.

The cross webs or wall sections 33 which intersect the center wall 10 can be seen in elevation in Fig. 2, top view in Fig. 1, edge view in Figs. 9 and 10, and center section in Figs. 3, 4, and 6. Each cross wall 33 is shaped, as seen in Fig. 2, to conform generally to the cross section of the tray 34. At the top center of each cross wall 33 there are two portions 35 and 36 projecting toward each other over a squat T-slot having a lower portion 37 and an upper portion 38. At the bottom center of each wall piece 33 there is a notch 39. A lip 40 is struck out of each cross partition 33 just above the notch 39. A shallow corrugation 71 is formed in each cross wall 33 below and generally parallel to its upper edge. The cross walls 33 are formed by a press operation and may be made of 61ST sheet aluminum .032" in thickness.

A cross wall 33 is inserted in each of the slots 13 in the center wall 10. The notches 39 at the bottom of the cross pieces 33 straddle the ribbon 15 at the bottom of the longitudinal partition 10. The lips 40 hook under the center piece at the top of the slots 11, as seen in Fig. 3.

Referring now to Fig. 5, a small metal strip 41 has two aligned slots 42 and 43. These slots are spaced from each other a distance equal to the distance between the ears 21 and 22 on the center wall 10. The slot 42 receives the ears 20 and 21, and the slot 43 receives the ears 22 and 23. These slots are just long enough to permit the ears to

spread apart from their positions in Fig. 3 to their positions in Fig. 4. The strip 41 lies in the lower portions 37 of the T-slots in the two center cross walls 33. As seen in Figs. 9 and 10, another similar strip 44 is in the same manner associated with the two cross walls 33 at the right hand end of the grid and its two slots engage respectively with the ears 24 and 25 and the ears 26 and 27. Another slightly longer strip 45 is associated with the two left hand cross walls 33 and engages in one slot the ears 16 and 17 and in the other slot the ears 18 and 19. The left hand end of the strip 45 is so slotted as to straddle the upstanding section 28 of the center wall 10 as seen in Fig. 6.

A long strip 46 overlies the top of the center wall 10 and is located in the upper portions 38 of the T-slots in the cross walls 33. As best seen in Fig. 1, the long strip 46 is suitably notched to permit insertion of this strip in the slotted cross walls. The right hand end of the strip 46 is provided with a slot dimensioned to receive the ear or lug 31 near the right hand end of the center wall 10. The strip 46 abuts the lug 32 at the right hand end of the center wall 10, and the lug 31 is peened over to fasten this end of the strip in place. The strip 46 has two slots 47 and 48 which receive the ears 23 and 24 of the center wall 10, and two other similar slots 49 and 50 which receive the ears 19 and 20 as seen in Figs. 9 and 10. The left hand end of the strip 45 is fashioned as a knob 51 as seen in Figs. 7 and 8. The slots 49 and 50 are also seen in Fig. 8.

The short strips 41, 44 and 45, called stop straps, may be made of 52SH aluminum sheet .09" in thickness. The long strip 46, called a thrust bar, may be made of 52SH aluminum sheet .06" in thickness. The stop straps fit nicely in the portions 37 of the cross wall T-slots, and thereby aid in preventing wobble of the cross walls relative to the center wall.

Referring to Figs. 9 and 10, and more particularly Figs. 6, 7, and 8, the knob 51 at the left hand end of the thrust bar 46 is designed to be engaged by a U-strap 52 which is formed with a notch 53 at its closed end to receive the shank of the knob 51. The legs of the U-strap 52 are pivotably connected by pins 54 and 55 to the forked ends of a handle 56. Two fingers 57 and 58 project downward from the legs of the strap 52 and curve forward and inward so that the ends of these fingers engage beneath the stop strap 45 on each side of the center wall 10. The U-strap 52, generally referred to as a yoke, may be formed of 52SH aluminum sheet .06" in thickness.

The handle 56 may be formed of like material to the shape seen in Figs. 1, 6, 7, 9 and 10. The pins 54 and 55 which pivot the yoke 52 to the handle 56 project through both flanges of the handle forks. These forks are located astride the upward projecting portion 28 at the left hand end of the center wall 10. The inner flanges 59 and 60 of the handle forks are journaled on a pin 61 which projects through the hole 29 in the center wall. The outer flanges of the handle 56 are provided with openings 62 and 63 to permit insertion of the pin 61 upon assembly. The openings 62 and 63 uncover the pin 61 or the holes for this pin when the handle 56 is about in the position illustrated in Fig. 10. The several pins may be 17ST aluminum rivets. The rivets 54 and 55 should be about $\frac{1}{8}$ " in diameter and the rivet 61 considerably larger in diameter, at least $\frac{3}{16}$ ".

The various parts of the grid, except the rivets,

are made by blanking and forming press operations. To assemble a grid, six cross walls 33 are forced downward in the upright curved slots 13 in the center wall 10 until the lips 40 snap into place in the slots 11. All of the cross walls may be the same, or one cross wall like that shown second from the right in Figs. 1, 9 and 10 may have upward projections 64 and 65 for the purpose of providing, together with the handle 56, a stable support for stacking another tray on top of the grid. Then the stop straps 41, 44 and 45 are placed in position as described above and the thrust bar 46 also located in its above described position. The handle 56 and the yoke 52 are assembled by means of the rivets 54 and 55. Then the yoke 52 is engaged with the knob 51 on the end of the thrust bar 46, and the handle located astride the upward projection 28 on the center wall 10. The handle is held in a position about like that in Fig. 10 so that the rivet 61 can be located by manipulation through the holes 62 and 63 in the handle. Then the fingers 57 and 58 are bent inward to engage beneath the stop strap 45. When the handle 56 is turned to its position shown in Figs. 1 and 9, the grid is closed and ready for use in the tray 34.

When using 52SH aluminum for the center wall and stop straps, it is desirable to provide a small piece 66 of 61ST aluminum in the handle end of the slot in the stop strap 45 in front of the ear 16. This filler piece 66 can be seen in Fig. 6 and is in the shape of a small inverted T with the leg projecting upward in the slot in the strap 45 in front of the center wall ear 16. The purpose is to decrease wear at this point.

It also has been found desirable to provide small shoes on the cross wall projections 35 and 36 above the thrust bar 46. These small shoes 67 and 68 on the projections 35 and 36 respectively, see Figs. 2, 3, and 4, are formed by turning short horizontal projections from the lower edges of the projections 35 and 36.

Another feature that has been found desirable is a light frictional engagement between the handle 56 and another part of the grid such as, for example, the forward end of the stop strap 45. This is accomplished by shaping the inside pair of downward flanges 59 and 60 on the handle to rub on the forks 69 and 70 of the strip 45 as seen in Figs. 6 and 9. The purpose is to dampen any snap action when the grid is manipulated without ice.

The above described linkage of the handle 56 with the yoke 52 on the upper projection 28 of the center wall 10 is a toggle arrangement. When the handle 56 is in the position shown in Fig. 9, it is held there by the overcenter action of the toggle arrangement. The center wall 10 is straight and the resilient cross walls 33 are held in flexure. It can be seen in Figs. 1, 3, and 9 that the cross walls 33 are curved from top to bottom. Although I have shown one corrugation 71 on each cross wall, several such corrugations may be provided. The purpose is to distribute toward the outer ends of the cross walls the curved flexure imparted to each cross wall at its center by the center wall 10.

Assume that the tray 34 has been filled with water and the water frozen to ice so that the tray 34 contains a block of ice with the grid embedded therein. When it is desired to obtain ice pieces, the handle 56 is pulled toward the position shown in Figs. 6 and 10. This urges the pins 54 and 55 to rotate around the larger pin

61 and exert pressure on the yoke 52 and the thrust bar 46. This force is transmitted through the thrust bar to the far end of the grid so that the ends of the grid are urged away from each other, causing the center wall 10 to try to bow upward in the middle and the slots 13 spread apart. The cross walls 33 try to straighten and unflex toward their flat positions illustrated in Figs. 4, 6, and 10. It can now be seen that the walls 33 could be normally curved and the slots 13 straight to afford the same effect. That is, the cross walls could be under flexure when straight, and unflex toward their curved positions. As the grid bows, the thrust bar 46 also bows since it is confined within the slots in the tops of the cross walls 33. As the sections of the center wall between the slots 13 try to fan out, and the cross walls 33 try to flatten, the adhesion of the ice to the grid walls and the tray walls is overcome and there results a grid filled with loose ice pieces. The grid containing the loose ice cubes can be lifted from the tray 34. One or more of the corner cubes may fall out of the grid but the others stay in the grid to be picked off in whatever number they are desired. Ice cubes not removed from the grid can be returned to the tray without handling of the cubes.

The distance the upper ends of the center wall slots 13 spread apart is limited by the several stop straps 41, 44 and 45. This function of the stop straps being understood, it will be seen that they can be provided in various forms. The requirement is linkage to limit the distance that the ears at the upper ends of the center wall slots 13 move apart when the center wall is bowed upward.

The series of slots 11 and 12 aligned generally lengthwise of the center wall 10, together with the upright slots 13, permit this wall to be flexed in its own flat plane. The cuts 14 also fan out when this wall is flexed. The degree of separation at the cuts 14 is a function of the length and location of the slots 12. The wall separation at the cuts 14 upon operation of the grid introduces forces tending to aid in breaking ice bonds on the center wall.

Various changes and modifications may be made within the scope of the following claims.

I claim:

1. An ice tray grid having a series of resilient transverse walls, parts including a longitudinal wall member intersecting said series of transverse walls and holding the latter in flexure, said parts being movable to unflex said walls to loosen ice attached thereto.

2. An ice tray grid having a series of resilient walls, a distortable longitudinal wall member intersecting said series to form a plurality of cells, said longitudinal wall member being formed to hold said series of walls in flexure, and means operable to distort said longitudinal wall to unflex said series of walls to loosen ice in said cells.

3. An ice tray grid distortable to loosen ice pieces formed therein with linkage operable to distort the grid and including a bendable thrust member confined against buckling by engagement at a series of points along its length with the grid, and means for applying a force in thrust to said member to distort the grid.

4. An ice tray grid flexible by opposite forces applied at its ends with a lever mounted on one end of the grid and a flexible member joining the lever to the other end of the grid and confined against buckling by sliding engagement at a series of points along its length with the grid.

5. An ice tray grid having a longitudinal wall member and cross wall members associated therewith to form cells for freezing ice pieces, said longitudinal wall member comprising a single piece of material inherently rigid in the plane of the wall and so formed as to permit bowing in the plane of the wall.

10 6. An ice tray grid having a series of cross walls intersected by a center wall with the latter formed from a single strip of material having a series of upright slots in which the cross walls are located and a series of aligned slots generally parallel to an edge of the center wall permitting bowing of the wall in its own plane.

15 7. A grid for an ice tray comprising a center wall formed of a single strip of material having a series of parallel slots each open at the top edge of the wall and projecting in an arc downward to a point in the lower part of the wall and also having a second series of aligned slots generally parallel to the bottom edge of the wall and intersecting the lower ends of said first series of slots, a series of resilient cross walls each held in flexure in one of said first series of slots

20 25 and notched at the bottom to straddle the lower part of the center wall, a series of stop links joining adjacent portions of said center wall at the upper ends of said first series of slots, said links also engaging said cross walls, and means operable to bow said center wall in its own plane and thereby spread said first series of slots to the extent permitted by said links to unflex said cross walls.

30 35 8. A flexible ice tray grid with a series of cross walls intersected by a center wall formed of a single piece of material having sections between the cross walls which fan out when the grid is flexed and links engaging the center wall sections in a manner to limit the extent of separation and also engaging the cross walls in a manner to prevent wobbling of the latter with respect to the center wall.

40 45 9. An ice tray grid having a series of cross walls intersected by a center wall with the latter formed from a single sheet of material having a series of upright slots in which the cross walls are located and a second series of slots arranged to permit bowing of the center wall in its own plane and with links engaging both the center wall and the cross walls in a manner to limit the extent of bowing of the center wall and hold the cross walls perpendicular to the center wall.

50 55 10. An ice tray grid with a resilient wall intersecting a second wall formed to hold the resilient wall in flexure during formation of ice in the grid, said second wall being distortable to unflex the resilient wall to effect release of the ice.

60 65 11. An ice tray grid with a resilient wall and mechanism to flex and unflex said wall, said mechanism including a handle and linkage which locks the wall in flexure during formation of ice in the grid.

12. An ice tray grid with a flexible wall intersecting a second distortable wall so formed as to flex the flexible wall when not distorted, and mechanism including a handle and linkage which restrains said second wall from distortion during formation of ice in the grid, said mechanism being operable by its handle to distort said second wall to unflex the flexible wall to effect release of the ice.

70 75 13. An ice tray grid having a series of cross walls and a center wall formed from a strip of material inherently rigid in the plane of the wall

and having a series of slots arranged to permit bowing of the wall in its own plane.

14. An ice tray grid as set forth in claim 13 in which the cross walls are located in some of said slots, the others of said slots being located between said cross walls to promote release of ice from the center wall by spreading upon bowing of the wall.

15. An ice tray grid having a one-piece wall formed of inherently rigid material and slotted to permit bowing of the wall and promote release of ice from the wall by spreading when the wall is bowed.
